C. W. YERGER

MOTOR CONTROLLER

Filed Dec. 18, 1918

Fig. 1.

UNITED STATES PATENT OFFICE.

CHARLES W. YERGER, OF WASHINGTON, DISTRICT OF COLUMBIA, ASSIGNOR TO THE CUTLER-HAMMER M'F'G CO., OF MILWAUKEE, WISCONSIN, A CORPORATION OF WISCONSIN.

MOTOR CONTROLLER.

Application filed December 13, 1918. Serial No. 267,308.

To all whom it may concern:

Be it known that I, CHARLES W. YERGER, a citizen of the United States, residing at Washington, in the District of Columbia, have invented new and useful Improvements in Motor Controllers, of which the following is a full, clear, concise, and exact description, reference being had to the accompanying drawing, forming a part of this specification.

This invention relates to motor controllers and more particularly to controllers for associated motor driven mechanisms adapted to co-operate cyclically, of which class of mechanisms rolling mill hotbeds may be taken as exemplary.

In the operation of certain types of hotbed, it is customary to deliver the finished shapes to the center of the hotbed and to provide means for shifting successive shapes to opposite sides of the hotbed, means being provided for their further disposition and distribution, and the present invention contemplates the provision of a controller for rendering the action of the aforesaid or other similarly correlated instrumentalities fully automatic.

A further object is that of providing a controller of the character stated wherein provision is made for rendering all or certain of such instrumentalities either active or inactive at will.

A further object is to provide a controller of the character stated operable for effecting operation of either side of the hotbed to the exclusion of the other side and to provide remote control means for supplementing the automatic control under such conditions of operation.

A still further object is that of providing a controller of the aforesaid character wherein provision is made for the substantially uniform disposition of the shapes or materials to be handled irrespective of variations in certain of the physical characteristics thereof.

Other objects and advantages will hereinafter appear.

In the accompanying drawing, wherein is illustrated an embodiment of the invention,

Figure 1 is a schematic illustration of a typical hotbed arrangement, while,—

Fig. 2 is a diagrammatic illustration of the control mechanism.

55

Referring to Figure 1, the features of the hotbed which are essential to the instant disclosure include a center section indicated generally at 1 and a pair of similar side sections 2 and 3. The center section includes a set of rolls 4 to receive the finished shapes from the rolling mill, together with a trigger mechanism 5 for shifting successive shapes to the side sections 2 and 3 alternately, the latter being provided respectively with shift bars 6 and 7 for moving the shapes outwardly from one notch of either side section to the next. The aforesaid mechanisms are separately driven through suitable gearing, by three motors, 70 namely a small motor 8 for operating the trigger mechanism and large motors 9 and 10 for operating the respective shift bars. The driving connections for the respective motors include countershafts 11, 12 and 13 75 respectively provided with cams 14, 15 and 16.

The cam 14 co-operates directly with the trigger mechanism and is arranged to effect one complete operation thereof in either direction for each half turn of the countershaft, the succeeding half revolution of said shaft effecting similar but reverse actuation of said trigger mechanism, while the cams 15 and 16 are adapted upon each complete 85 revolution thereof to effect both operation of their respective shift bars and return thereof to initial position.

A plurality of drum controllers acting in response to varying hotbed conditions, 90 serve in conjunction with other control elements to be hereinafter described, for controlling the several motors to provide cyclic operation of the hotbed mechanisms both individually and collectively.

The aforesaid drum controllers include an oscillatable starting master controller 17 biased to a predetermined circuit closing position and movable therefrom to a different circuit closing position by each of the successively arriving shapes prior to full delivery thereof to the center rolls 4, a con-

95

100

troller 18 to be rotated by motor 8 from counter shaft 11 at the speed of the latter, and controllers 19 and 20 driven respectively by large motors 9 and 10 through gearing of such ratio as to provide one-half revolution of each of said controllers for each complete revolution of the respective counter-shafts 12 and 13.

The operating means for the master controller 17 include an oscillatable apron 21 to be lifted by each of the successively arriving shapes to be handled, and to be released for biased return movement as each successive shape arrives fully upon the center rolls, the circuit connections controlled by said master controller being such as to require both lifting of said apron and return thereof to its biased position in order to initiate the cycle of operation of the hotbed.

As illustrated in Fig. 1, the shift bar 7 is at rest and the trigger mechanism is also at rest after shifting the last delivered shape to the side section 3, while the shift bar 6 is just completing the operation of moving further to the right the shapes previously delivered to section 2. The next shape is still in transit between the rolling mill and the center rolls, the apron 21 being maintained in elevated position thereby. As the end of said shape clears said apron the latter resumes its biased position, thus completing the double operation of the master controller 17 for starting the small motor 8 to shift said shape to the first notch of section 2 of the hotbed. Upon completion of such operation the small motor is automatically stopped by the controller 18 which also serves in the interim to provide for starting of the large motor 10 to actuate the shift bar 7 for moving the shapes upon section 3 farther to the left, stopping of motors 9 and 10 upon completion of the operation thereof being effected automatically by their respective controllers 19 and 20.

Referring now to Figure 2, the motors 8, 9 and 10 are of similar construction differing only in size and power. Said motors are supplied with current from line L' through electro-responsive main switches 22, 23 and 24 respectively and are respectively provided with series fields 25, 26 and 27 and with one or more steps of starting resistance 28, 29 and 30, said resistances being respectively controlled by means of suitable lock-out switches 31, 32 and 33. Said motors are furthermore provided with dynamic braking circuits controlled respectively by means of electro-responsive switches 34, 35 and 36 biased to circuit closing position and each having an opening winding connected in parallel with the main switch closing winding of its associated motor to provide for simultaneous and opposite action of the switches controlling any motor upon closure

or interruption of a single joint energizing circuit.

The joint energizing circuit of the main and dynamic braking switches of motor 9 is adapted to be controlled through either one of a pair of similar relays 39, 40; the corresponding circuit for motor 10 is similarly controllable by means of relays 41, 42; while for motor 8 the corresponding circuit is controllable through similar relays 37, 38 supplemented by the contacts *a* of master controller 17 in a manner and for purposes hereinafter stated.

The contacts *b* of said master controller are adapted to make temporary connections for the energizing circuit of relays 37 and 38 jointly to one supply line, each of said relays being provided with auxiliary contacts adapted when the relay is closed to maintain its said line connection, while the contacts *c* and *d* of controller 18 serve to control the connection of said circuits selectively to the other supply line.

The arrangement of said contacts *c* and *d* is such that the winding of one relay is always disconnected from line L^2 for de-energization thereof upon 180° travel of the drum from the position in which the winding of the other relay was previously disconnected. This action provides for stopping of motor 8 upon completion of one operation of the trigger in either direction. Moreover, said contacts *c* and *d* overlap one another at either end as illustrated, thereby insuring that for any position of the drum the winding of one relay at least is connected with line L^2 , while for certain positions of the drum both relay windings are so connected. This arrangement insures that irrespective of the position in which the motor 8 and controller 18 may be stopped, the latter always provides for restarting of the former through suitable actuation of master controller 17, and also provides for continuous operation of the motor under certain conditions.

The contacts *e* of the controller 18 co-operate with controller 19 to provide similar control of relays 39 and 40 and the contacts *f* of controller 18 act similarly in conjunction with controller 20 to determine the action of relays 41 and 42, thus providing similar cyclic operation of motors 9 and 10 and the respective shift bars 6 and 7 driven thereby.

From the foregoing, it is apparent that cyclic operation of the individual sections of the hotbed is effected by means of the drum controllers respectively driven thereby, whereas the controller 18 serves additionally to co-ordinate the cycles of said individual sections for providing cyclic operation of the hotbed as a whole, said controller acting, during each operation of the

trigger mechanism, to initiate action of the shift bar on that side of the hotbed to which the last preceding shape was moved by said trigger mechanism.

- 5 The energizing circuits of the respective pairs of relays are also provided with starting push switches 43, 44, 45 and with stop switches 46, 47, 48, the latter having locks for releasably retaining the same in open position. By means of the foregoing manually operable switches any or all of the motors may be started, stopped or locked against operation at will, thus providing for remote control of the hotbed mechanism, 10 15 said remote control features being operable in lieu of any or all of the corresponding automatic elements as desired.

The power circuits of the three motors are precisely similar while the control circuits 20 thereof are also in general similar, except for their manner of connection with the various drum controllers.

- Upon closure of main switch 22 of motor 8 and opening of its dynamic braking switch 25 34 the circuit of said motor is completed, said circuit being from line L' by conductor 49 through the upper contacts of said main switch, thence by conductors 50 and 51 through said motor by conductors 52 and 53 through the lower contacts of said main switch, by conductor 54 through series field 25, thence by conductor 55 through the windings of lockout switch 31, by conductor 59 through series resistance 28 to line L². 35 As the starting current decreases due to motor acceleration the lockout switch 31 responds, short-circuiting resistance 28 and its own lockout winding in a well known manner, the motor circuit thereafter extending through said switch and by conductor 60 to line L². Upon opening of the main switch 22 and closing of dynamic braking switch 34 the dynamic braking circuit of said motor is completed, said circuit being from the 40 45 right hand brush of the motor by conductors 52 and 53 through the lower contacts of switch 34, thence by conductor 61 through series field 25, by conductor 54 through the upper contacts of switch 34 and thence by conductors 50 and 51 to the left hand motor brush. The power circuits of motors 9 and 50 55 60 65 70 75 80 85 90 95 100 105 110 115 120 125 130 being similar to the foregoing will not be specifically traced herein.

The finished shape in its travel from the rolling mill to the center rolls 4 first engages and lifts the apron 21, thereby moving the master controller 17 to the position illustrated for causing engagement of its contacts b. Such action completes the energizing circuit of relay 37, said circuit extending from line L' through stop push button 46, thence by conductors 62 and 63 through the upper contacts b of said master controller, by conductor 64 through the 65 70 75 80 85 90 95 100 105 110 115 120 125 130 winding of relay 37, thence by conductor 65

through contacts c of controller 18 and by conductor 66 to line L². Said relay thereupon responds and maintains itself through circuit connections independent of master controller 17, said maintaining circuit extending from stop push button 46 by conductors 62 and 67 through the auxiliary contacts of said relay, thence by conductor 64 through the winding of said relay and to line L² as formerly traced. Closure of 70 75 80 85 90 95 100 105 110 115 120 125 130 said relay, however, does not cause starting of motor 8, such action being dependent upon return of master controller 17 to its normal position, which occurs upon passage of the shape from beneath the apron 21. Assuming such movement of said apron and said controller the joint energizing circuit of main switch 22 and dynamic braking switch 34 is completed, said circuit extending from line L' by conductors 49 and 68 through relay 37 which is now closed, thence by conductors 69 and 70 through contacts a of master controller 17, by conductor 71 to the junction of conductor 72 therewith, thence by parallel conductors 71 and 72 through the windings of said main switch and said dynamic braking switch and by conductors 73, 74 and 66 to line L². Said main switch thereupon closes and said dynamic braking switch opens thus completing 90 95 100 105 110 115 120 125 130 the power circuit of motor 8 as already traced. Closure of main switch 22 also serves to complete a maintaining circuit therefor and for dynamic braking switch 34, said circuit extending from line L' through relay 37 as formerly traced, thence by conductors 69 and 70 through the auxiliary contacts of said main switch, thence by conductor 75 through the windings of said main and dynamic braking switches and to line L² as formerly traced. Motor 8 thereafter operates to drive the trigger mechanism for shifting the shape to the right.

The driving connection between said motor and the controller 18 is such that upon full movement of the trigger mechanism to the right, said controller operates to interrupt the maintaining circuit of relay 37 which thereupon opens and interrupts the maintaining circuits of main switch 22 and dynamic braking switch 34 for stopping and dynamic braking of the motor.

However, prior to such de-energization of relay 37, the controller 18 acts to connect the winding of relay 38 with line L² as previously described to provide for restarting of motor 8 through subsequent closure of said relay upon operation of master controller 17 by the next arriving shape.

Also, practically at the inception of the afore-described trigger operation, the controller 18 by means of its contact f, causes starting of motor 10 through energization of relay 41, thereby causing operation of shift-bar 7 of the hotbed. However, since

the shift bar 6 driven by motor 9 is illustrated as in operation with its control circuits in operative relation, such circuits of the latter motor only will be considered, the control circuits of these two motors being similar.

The energizing circuit of relay 40 controlling the motor 9 extends from line L' by conductors 76 and 77 through contacts e of controller 18, thence by conductor 78 through the winding of relay 40, by conductor 79 through the lower contacts of controller 19 and thence by conductors 80 and 81 to line L^2 . Said relay thereupon closes and maintains itself by circuit connections extending from line L' through stop push button 47 thence by conductor 82 through the auxiliary contacts of said relay, by conductor 78 through the winding of said relay and thence to line L^2 as last traced. Closure of said relay completes the joint energizing circuit of main switch 23 and dynamic braking switch 35, said circuit extending by conductors 76 and 86 through said relay, thence by conductors 87 and 88 to the junction of conductor 89 with the latter, thence in parallel through the windings of said switches and by conductors 90, 91, 80 and 81 to line L^2 .

30 Since from inspection of Fig. 2 it is obvious that the starting push switch circuits for the individual motors merely parallel the corresponding automatically controlled circuits, whereas each stop push switch is arranged, upon opening, to interrupt the maintaining circuit connection of both of its associated relays with results as aforescribed, further discussion of these circuits is deemed unnecessary.

40 It is also obvious that both relays of the several pairs perform precisely similar functions and are energized through parallel circuits, selection between the relays of each pair being determined solely by the positioning of the respective controllers, the contacts of said controllers being arranged to insure establishment of return circuit connections for the relay which is open prior to interruption of the return circuit of the 50 relay which is closed. This arrangement, as regards motors 9 and 10, provides for operation of each countershaft through a complete revolution and permits the use of a single controller to effect stopping of each 55 motor always at the same position while providing for restarting from said position.

As applied to the motor 8, the aforescribed arrangement of the two relays, in conjunction with the overlapped relation of 60 the lower contacts of controller 18 and the double throw characteristic of master controller 17, additionally serves to insure operation of the device, and particularly the trigger mechanism, in complete cycles irrespective of variations in the time element

between the arrival of successive shapes upon the center rolls, such variations being likely to occur particularly during the handling of shapes of varying lengths.

Thus if at any time the apron 21 is lifted and held up by an arriving shape before the trigger mechanism has completed its movement for disposal of the preceding shape, the relay which is open will close as soon as controller 18 reaches its lap position and will remain closed without in any wise affecting the operation then in progress, whereas upon subsequent release and descent of said apron the circuit through said relay is completed, thereby restarting or continuing the operation of motor 8 for driving the trigger mechanism in the reverse direction.

While the afore-described features of the controller thus serve to compensate for variations in length of the shapes to be handled, it is obvious that the swinging apron 21 is adapted to operate uniformly irrespective of wide variations in the height or thickness of such shapes, whereas variations in lateral width of shapes within the capacity of the center rolls in no wise affects the operation of the controller.

Should it be desired to operate only one side of the hotbed, the stop button controlling the operating motor for the opposite side of the bed is locked in open position, thus insuring against operation thereof. Thereafter following operation of the motor 8 to shift the finished shape to the active side of the hotbed the operating motor for that section is automatically started by means of controller 18 as aforescribed. However, prior to the arrival of the next shape upon the center rolls the motor 8 must be started manually for returning the trigger mechanism to its former position and also providing return of the controller 18 to a position insuring subsequent starting of the large motor which has last operated.

It is, of course, to be understood that the dynamic braking means disclosed herein might be supplemented by other braking means if desired and that other types of motors more readily controllable for dynamic braking might be employed in lieu of the series motors illustrated. Also, it is to be understood that the master controller might be operated in other ways and that the timing action thereof with reference to the arrival of successive shapes upon the center rolls might be varied to meet requirements.

What I claim as new and desire to secure by Letters of Patent is:

1. In a controller for motor driven handling devices, in combination, means providing for cyclic operations of the controlled device including motor control means subject to control through independent sets of instrumentalities, said sets being adapted to participate successively in the control and

selectively throughout equal ranges of operation of the controlled device and means to act automatically upon said instrumentalities during operation of the device for rendering effective a set for participation in the control throughout the next cyclic operation and thereafter rendering ineffective the set participating in the current operation for terminating such operation, and independently controlled means to act upon said instrumentalities for timing the initiation of the next cyclic operation.

2. In a controller for a rolling mill hotbed having a plurality of sections operable by separate motors, the combination with motor control means providing for cyclic operation of the several sections both individually and collectively for disposal of the shapes delivered thereto, of means for timing the initiation of such cyclic action with reference to the time of delivery of each successive shape to the hotbed.

3. In a controller for a rolling mill hotbed having a plurality of sections operable by separate motors, the combination with motor control means providing for cyclic operation of the several sections comprising limit switches to be driven in synchronism with the respective sections to provide for starting and stopping of each section uniformly at a given point, of control means to be driven in synchronism with one of said sections for co-ordinating the cycles of the other sections sequentially with respect to the cycles of said former section, and means to act automatically for timing the starting of said former section with reference to the moment of full delivery to the hotbed of each successive shape to be handled.

4. In a controller for a rolling mill hotbed having a plurality of sections operable by separate motors, the combination with motor starting means, of means providing for cyclic operation of the several sections, said latter means including individual controllers for the motors, each of said controllers comprising sets of relatively movable co-operating contacts, the contacts of each set being adapted to disengage one another upon completion of a predetermined range of operation of the section controlled thereby for terminating the cycle thereof, and to re-engage one another during a subsequent cycle to provide for initiation of a later cycle by said starting means, the control of each section shifting progressively from one to another set of contacts of its associated controller.

5. In a controller for a rolling mill hotbed having a plurality of sections to be driven by separate motors, the combination with starting and range limiting means for said sections providing for cyclic operations thereof and including controllers having individual starting switches and limit switches

for the several motors, of mechanical connections between certain of said switches for correlating the cycles of said sections to provide cyclic operation of the several sections for progressive action thereof upon the successive shapes to be handled thereby.

6. In a controller for a rolling mill hotbed having a plurality of sections to be driven by separate motors, the combination with starting and range limiting means for said sections providing for cyclic operations thereof comprising controllers to be driven in synchronism with the respective sections and including individual motor starting switches and limit switches, of means connecting certain of said starting switches with certain of the limit switches so driven for correlating the cycles of said sections for progressive action thereof upon the successive shapes to be handled thereby, and means for actuating another of said starting switches automatically upon delivery of each shape to the hotbed.

7. In a controller for rolling mill hotbeds having a plurality of sections to be driven by separate motors, the combination with starting and range limiting means for said sections providing for cyclic operation thereof and including individual starting switches for the motors and limit switches to be driven in synchronism with the respective sections, each limit switch including a plurality of sets of relatively movable contacts, each set of contacts being adapted to co-operate for controlling the action of its associated section throughout one cyclic operation, such control shifting from one set of contacts to another set during each cyclic operation to provide for initiation of the next, of means for connecting certain of said starting switches with certain of the limit switches for co-ordinating the cyclic operations of said sections to provide for progressive action thereof upon the successive shapes to be handled thereby.

8. In a controller for a rolling mill hotbed having a central section and a pair of similar side sections, said sections to be driven by separate motors, the combination with limit switches to be driven in synchronism with the respective sections for stopping of each after a predetermined operation and to provide for restarting thereof from the position of stopping, of an automatic starting switch for said central section to be actuated by the successively arriving shapes to be handled, and separate switches for the respective side sections each to be driven in synchronism with said central section to provide for starting of said side sections alternately and each after one complete operation of said central section.

9. In a controller for motor driven conveyors, the combination with independent sets of circuit connections adapted to pro-

vide selectively for control of the motor circuit, of a controller for said connections including a plurality of contacts to be driven in synchronism with the controlled device and adapted to interrupt one set of said connections to effect stopping of said device upon operation thereof to a predetermined degree, and prior to such stopping to preselect another set of said connections to provide for restarting, and independent means to act upon said sets of connections jointly for completing the connections preselected by said controller contacts for restarting of said device.

10 15 20 25 30 35 40 45 50 55 60 65

10. In a controller for motor driven conveyors, the combination with independent sets of circuit connections adapted to provide selectively for control of the motor circuit, of a controller for said connections including a plurality of contacts to be driven in synchronism with the controlled device and adapted to interrupt one set of said connections to effect stopping of said device upon operation thereof to a predetermined degree, and prior to such stopping to preselect another set of said connections to provide for restarting, and independent means to act upon said sets of connections jointly for completing the preselected connections either before or after interruption of the completed circuit by said controller, to provide respectively for continuous or cyclic operation of the controlled device.

11. In a controller for motor driven conveyors, the combination with independent

sets of circuit connections adapted to provide selectively for control of the motor circuit, of a controller for said connections including a plurality of contacts to be driven in synchronism with the controlled device and adapted to interrupt one set of said connections to effect stopping of said device upon operation thereof to a predetermined degree, and prior to such stopping to preselect another set of said connections to provide for restarting, and independent means operable either automatically or manually at will to act upon said sets of connections jointly for completing the preselected connections either before or after interruption of the completed circuit by said controller, to provide respectively for continuous or cyclic operation of the controlled device.

12. In a controller for motor driven conveyors, the combination with switches for controlling the circuit of the driving motor directly, of automatic control means for said switches comprising a pair of relays adapted to effect similar control of said switches, a controller to be actuated by the successive shapes delivered to the conveyor for joint control of said relays and selective control means for said relays to provide for energization and de-energization thereof alternately upon predetermined operation of the controlled device.

In witness whereof, I have hereunto subscribed my name.

CHARLES W. YERGER.
